Application January 16, 1935, Serial No. 2,003
In Canada December 24, 1934

16 Claims. (Cl. 13—6)

The present invention relates to the construction and operation of electric furnaces of the single or polyphase type such as may be used for the manufacture of glass, sodium silicate or other products.

5 The principal object of the invention is to construct and operate a furnace of the above type so as to maintain the charge or other material in the fusion zone at a uniform temperature without localized overheating or the formation therein 10 of overheated zones.

Another object of the invention is the arrangement of electrodes within such a furnace so that they will influence the flow of material from the reaction or melting zone.

15 Other objects will appear as the description proceeds and with reference to the accompanying drawings, showing several embodiments of the invention.

When constructing electric furnaces for the 20 manufacture of glass, sodium silicate and similar products, it is of the utmost importance that the temperature of the molten bath in the furnace chamber be as uniform as possible. This is necessary in order to avoid convection currents in 25 the bath, which latter may cause serious damage to the furnace lining and disturbance and hindrance of the chemical reactions taking place in the bath. Convection currents further tend to cause portions of the unmelted or unreacted 30 charge to pass through the furnace outlet, thus contaminating the final product. This desirable equalized temperature is particularly difficult to obtain in the operation of three or polyphase furnaces while in single phase operations a fairly 35 uniform bath temperature may be maintained by using heavy iron electrodes which have the effect of transferring the heat from the warmer places to the cooler ones.

In three or polyphase furnaces, however, such 40 heavy electrodes cannot be used as the cubical content of the electrodes can vary only within a relatively narrow range, which is controlled by the melting area, the electrode gap and operating voltage. The use of such heavy electrodes would 45 require a much larger melting area or fusing zone in the furnace and lower operating voltage than has been considered good practice in three phase furnace operation.

It has been further found to be of advantage 50 to increase the operating voltage over that considered suitable heretofore. Instead of the usual average of 60 to 70 volts, satisfactory results have been obtained between a voltage range of 120 to 130. This, of course, permits of the use of 55 smaller electrodes and less electrode contact surface. One disadvantage, however, of the use of this smaller contact area is that the electrical load per square unit of electrode contact surface reaches a dangerous maximum.

When operating single phase furnaces, it has been considered that the maximum electrical load should not at any time exceed 5 to 6 amperes per square inch of electrode area. This precaution has been taken to avoid electrode overheating which might otherwise possibly cause a melting of 5 the electrode and consequent decomposition or contamination of the material of the bath itself. In order to make three phase furnace operation commercially acceptable, it has been necessary to double the electrical load to from 10 to 12 10 amperes per square inch of electrode area, so that the volume of the electrodes and the area of their contact surfaces will correspond with the optimum furnace melting area and operating voltage. It has, therefore, become necessary to use electrodes 15 less in volume and area, in many instances such reduction being $\frac{1}{4}$ of that used in single phase furnaces. The electrodes in three or polyphase furnaces, therefore, lack the desirable protection obtainable in single phase furnace electrodes by 20 reason of their larger volume. Consequently they tend to overheat with the formation of local overheated zones and undesirable convection currents.

While heat is generated more or less in all parts of the melting chamber, yet the bulk thereof will 25 be generated around the center part of each electrode gap. Consequently, in three phase furnaces containing three electrodes, three distinct heat zones will appear. This is to be expected inasmuch as the current density is greatest at these 30 points. Unfortunately, such heat zones tend to increase in intensity and size as the electrical conductivity increases with the heat and more current passes therethrough until an equilibrium is reached between the heat generated at those 35 locations and the heat removed therefrom either by conduction or radiation.

The material flowing from the melting chamber or fusing zone through the submerged throat into the tapping or refining chamber tends to have a 40 suction effect on the melt surrounding the throat in the melting chamber. This causes the melt closest to the throat to move faster downwardly toward the throat than in other parts of the melt. Consequently, more raw material moves in this 45 bath and will be fused at this point. The fusing process, which requires heat, results in cooling the molten mass, which, in turn, causes increased electrical resistance and less heat to be generated, 50 thus further intensifying the cooling effect.

The above mentioned causes tend to work in combination with each other and in actual operations temperature differences of 100° C. and more 55 in different parts of the furnace have been observed. This is serious in glass furnaces where it causes bubbles or seeds in the product.

It has also been found that, in order to enhance and maintain the uniformity of the temperature of the molten charge, it is advisable to apply heat 60

to certain parts of the furnace bottom not to an extent which would actually raise the temperature of the molten charge but rather to compensate for heat radiation or conduction.

5 Great care must be taken in designing the location of the furnace walls so that no substantial part of the current flow passes through such walls. If this precaution is ignored, serious deterioration of the walls due to 10 current flow has been actually found to have taken place in furnaces which have been torn down for repair or replacement. Calculations for such design to avoid this effect are more fully described in my copending patent application, Serial No. 719,076.

15 Sometimes it is impractical to locate the furnace walls entirely outside of this current path. In such event, the furnace walls should be placed as far away from this current path as possible, this path generally being theoretically not materially outside a semi-circle drawn from the center point of one electrode to the center point of an opposite electrode. If this semi-circle touches or tends to touch a wall, means should 20 be provided for cooling this particular part of the wall. This may be done by providing cooling ducts in the wall at that place or by substituting for insulation there, a material which will readily dissipate developed heat such as cast refractory 25 or the like.

30 The raw material fed to the furnace may be used as a means to decrease or increase the electrical conductivity of the resistance of the molten bath itself and this feature is also described in my copending application above mentioned. In any event, the raw material blanket covering the 35 surface of the melt should have such a minimum thickness that gases penetrating the same leave the blanket at substantially the temperature of the fresh raw material. It must, however, be thick enough that there will be no gas pockets 40 between the bottom of the blanket and the surface of the melt. This raw material may be evenly spread over the furnace by a motor driven charging car capable of being raised or lowered, 45 all as described in my above mentioned copending application.

To this end, the invention contemplates, with respect both to single and polyphase furnaces, 50 means for applying heat to the bottom of the melt, both in and outside of the reaction or melting chamber to compensate for heat losses through radiation or conduction.

The invention also contemplates the provision 55 of cooling means to avoid wall deterioration for those portions of the side walls through which the current flow passes or tends to flow.

The invention further revolves about the use of 60 electrodes having an upstanding plate-like extension, the volume of which has a certain proportion to the volume of that portion of the electrode submerged or in contact with the melt; also about having the connector bars of the electrodes located or extending out of or above the melt.

65 The invention contemplates with particular respect to polyphase furnaces, an arrangement of electrodes whereby locally overheated zones are avoided and a uniform melt temperature may be maintained. Where there is a tendency for heat 70 loss to occur at or near the submerged throat or outlet from the melting or reaction zone, the invention contemplates the arrangement of electrodes so that this heat loss may be avoided and the discharge from the furnace melting chamber 75 will proceed with uniformity without in any

way detracting from the desirable temperature uniformity of the entire melt.

The invention further consists in the novel arrangement and construction and combination of parts and operating details more fully hereinafter 5 described and shown in the accompanying drawings.

In the drawings:

Fig. 17 is a bottom plan view of the electrode of Fig. 15;

Fig. 18 is a side view of a modified form of electrode;

Fig. 19 is an end view of the electrode of 45 Fig. 18;

Fig. 20 is a bottom plan view of Fig. 18.

Referring now with particularity to the drawings, the difficulties usually encountered in a three electrode polyphase furnace are illustrated 50 in Fig. 1. Such a furnace is diagrammatically illustrated as having walls or wall-sections forming with a bottom-section a melting or reaction chamber 2 therebetween with a submerged throat 3, a refining chamber 4 and overflow 5. Electrodes 6, 7 and 8 which are substantially horizontally disposed and are suitably connected to a polyphase electric circuit are also provided. The normal location of these electrodes is one in which a horizontal triangle connecting the centers of the electrodes comprises a triangle whose angles are 60° so that they are directed toward a generally common center, electrode 7 being on a longitudinal center line of the furnace and in line with the submerged throat 3, the remaining electrodes being on each side thereof. Under these circumstances, a most unsatisfactory heat distribution occurs.

Due to the fact that the flow of the melt through the submerged throat 3 tends to be faster 70 than that of the melt in the remaining portion of the heat chamber, there is relative stagnation in those parts of the furnace away from the throat. The zones of greatest heat intensity are, of course, between the electrodes in the stagnant 75

zone. This, therefore, produces localized super-heated spots as indicated by the lines 9 and 10 between electrodes 6 and 7 and 1 and 8, respectively. The entire stagnant zone is indicated by the line 11. This makes, of course, zones of varying degrees of heat, in which zones 9 and 10 are the hottest, zone 11 is slightly cooler, while the remaining portion of the furnace chamber is still cooler. The coolest zone, which is over the furnace throat, is caused by the more rapid outflow of fused material through the throat causing additional quantities of the raw charge to be drawn down, and the fusion of the larger quantities of raw charge at this point absorbs heat to produce a cooling action on the charge at this point. In addition, in the warmer zone 11, convection currents will tend to be set up which, in combination with the down current in the colder zone immediately adjacent the throat, causes an increase of the temperature differential. The above makes for unsatisfactory operation which is directly reflected in the quality of the product.

Fig. 2 illustrates a furnace of the type shown in Fig. 1 but in which the heat balance has been vastly improved. Here the furnace layout is shown similar in some respects to that of the furnace of Fig. 1, except that immediately within the walls 1 a platform 12 is built up on the furnace bottom and electrodes 13, 14 and 15 rest on this platform. The platform 12 is not completely circular but is provided with spaced apart ends immediately adjacent the submerged throat 3. This produces a stepped melting or reaction chamber indicated generally at 16.

As will be observed, the gap between electrodes 13 and 15 has been shortened as compared with the gaps between electrodes 13 and 14 and 14 and 15. This tends to increase the heat generated between electrodes 13 and 15. This increased heat tends to overcome the cooling effect of the in-drawn raw material produced as a result of the suction effect of the melt passing through the submerged throat 3. It also results in a merging of all three heat zones between the electrodes into a single zone illustrated diagrammatically by the line 17.

While, of course, it is difficult to set down formulae whereby the exact location of these electrodes may be determined for all purposes, yet it has been determined that in a horizontal triangle connecting the centers of the electrodes, the angles made with the line connecting the two electrodes on each side of the submerged throat should be more than 60° , while the top angle of the triangle will be less than 60° . More specifically the electrode gaps x and y should be approximately the $\sqrt{2}$ times the electrode gap z .

In order to further enhance the uniform heating effect in such a furnace and to prevent undue deterioration of the furnace walls, it is desirable, as has been noted in my copending application Serial No. 719,076, that the walls of the furnace should be so spaced as to be out of the path of current flow. This flow may be represented diagrammatically by the semi-circles F connecting the center points of the electrodes. The deteriorating effect of the heat generated by the current flow where such flow tends to touch the walls may be greatly lessened by placing a cooling duct 18 between the inside refractory 19 and the outer metallic shell 20, or any desirable cooling means which will remove the heat from this section of the furnace wall. Cast refractory 21 may be used to serve the same function as the

cooling duct, this material being particularly efficacious in conducting heat away from the melting zone at that point. This material is also particularly resistant to the current flow itself, but rather than construct the entire inner lining 5 of this material, which would be rather expensive, blocks thereof may be inserted at the points of greatest wear.

Cooling ducts 22 may also be provided in the platform 12 to overcome any local overheating. 10 It is to be noted that these ducts pass immediately beneath the electrodes and serve to maintain those parts of the furnace adjacent thereto at a desirable temperature.

Fig. 3 illustrates a polyphase furnace having 15 four electrodes in which the walls are indicated generally at 1, the melting chamber or reaction zone at 2, the submerged throat 3 leading to the refining chamber 4 and overflow 5. A platform 12 is built up on the furnace bottom to receive the 20 electrodes 23, 24, 25 and 26. Electrodes 23 and 25 may be of larger volume and extent than electrodes 24 and 26 where desirable. In this arrangement, electrodes 23 and 25 are in line with the furnace center line A—A while electrodes 24 25 and 26 are in line with the furnace center line B—B. Electrodes 23 and 25 are each connected with a different phase in a three phase electrical circuit while electrodes 24 and 26 are connected to the same and remaining phase. 30

It is to be noted that the submerged throat 3 is in line with the gap between electrodes 23 and 25 and also passes beneath the former. This makes for a better heat control. By adjusting the contact areas of electrodes 23 and 25 with 35 relation to electrodes 24 and 26, the uniformity of heating effect may likewise be controlled.

An arrangement as described above tends to produce local heat zones of greatest intensity as illustrated by the lines 27, with a lesser heat zone 40 indicated by the line 28, the remaining portion of the furnace immediately surrounding the throat 3 being cooler. In a furnace of this general layout, however, these zones are not excessively objectionable, although the heat uniformity can 45 be improved by the arrangement shown in Fig. 4.

In that layout, the furnace dimension along the center line B—B is materially shortened over that of Fig. 3. This brings the electrodes 24 and 26 closer together with the result that the gaps between those electrodes and electrodes 23 and 25 are materially shortened. This has a tendency to bring the zones 27 closer together and the limits of zone 28 closer to the throat 3 which, as a consequence, materially decreases the cold zone 55 immediately surrounding the throat. This enlargement of the hot zone in the center of the furnace is very desirable.

While it is difficult to arrive at formulae for a most desirable location of the electrodes with regard to each other, yet it may generally be stated that the angle between the lines connecting the centers of electrodes connected to different phases should be approximately 90° . This may be expressed by saying that the length of the gap between the electrodes on the furnace center line A—A should be $\sqrt{2}$ times that of the average of the shorter gaps. 60

The same relationship of furnace wall to current flow should be observed with respect to that 70 described in connection with Fig. 2 as well as the various cooling means or ducts there provided.

To further equalize the temperature attained in the heat zones of a furnace of the type shown in Fig. 4, an electrode arrangement as shown in 75

Fig. 5 is preferred. By moving the electrodes 24 and 26 out of the furnace center line B-B and into the line parallel therewith but nearer the submerged throat 3, practically all localized heat zones are merged into a single zone of fairly uniform intensity. The top of this zone is illustrated by the line 29 and the bottom thereof by the line 30. The relationship in Fig. 5 as to electrode gap should be the same as above set forth in connection with Fig. 4. This adjustment is so sensitive that even a small movement of the electrodes out of the furnace center line B-B results in appreciable heat uniformity.

In Fig. 6, a three phase furnace is diagrammatically illustrated showing the walls 1 and the electrodes 23, 24, 25 and 26 in which electrode 23 is connected to phase A', electrode 25 with phase B', electrodes 24 and 26 with phase C'. In this arrangement, the effective area of electrodes 23 and 25 and their volume is materially greater than that of electrodes 24 and 26.

This larger effective area and volume may be secured in other ways than by making an integrally larger electrode.

In Fig. 7, the same furnace is shown in which the electrode 23 is subdivided into two individual electrodes both, however, connected with phase A as in the case of Fig. 6.

In Fig. 8, both electrodes 23 and 25 are of the multiple type connected, however, in the manner shown in Fig. 6.

In like manner, either or both of the electrodes 24 and 26 may be subdivided as shown in Figs. 9 and 10, respectively, wherein electrodes 24 and/or 26 are of the multiple variety. The above illustrates the wide diversification that may be practiced to secure the herein desirable effects.

A complete furnace embodying the principles herein described is shown in Figs. 11 to 14 inclusive.

In Fig. 11 the furnace shell is shown at 31 enclosing a composite wall made up of insulation material 32 with refractory lining 33. The major portion of the bottom of the furnace chamber 45 between the side walls is composed of refractory 33 mounted upon suitable insulation 32 rested upon supporting blocks 34. A portion of this refractory 33 surrounds the bottom immediately adjacent to said walls to form the platform 12 upon which the electrodes rest. Cooling ducts 35 are located in various parts of the furnace construction in order to produce the desired cooling effect where needed.

In order to compensate for any heat lost by radiation or conduction from the molten material when passing through the submerged throat 3, the bottom of the furnace immediately beneath and on each side of the submerged throat 3 is made of a more efficient heat conductor such as fused refractory 36. Immediately below are located a series of metallic blocks 37 such as iron or the like through which passes heating means such as carbon resistance 38 connected at the ends by carbon leads 39 to a suitable source of electric current. By generating heat at this point, any heat lost through radiation or conduction is resupplied. This makes for a uniformity of heating effect and, as a matter of fact, by increasing the heat at this point, the fluidity of the batch may be increased here. In like manner, heat may be supplied to the bottom of the refining chamber 4 or elsewhere as desired.

In order to induce flow through the submerged throat 3, the bottom of the melting chamber is

inclined toward the center to form a trough 40, leading to the throat 3.

In operation, the raw material is fed to the melting or reaction chamber by means of a charging car 41 suitably mounted for movement on rails 42 on the top of the furnace wall, this car being also mounted for vertical adjustment so as to maintain a desired thickness or blanket of raw material 43 on top of the melt. The level of the molten material in the furnace should preferably be such that the major portions of the electrodes are submerged therein while the connector bars of the electrodes are not. The upper portion of the electrode, however, which extends toward and outside of the furnace walls, desirably should be completely surrounded by the raw material blanket.

The melt flows through the submerged throat to the refining chamber 4, the level of which is maintained at the level of the discharge outlet 5 under the pressure action of the raw material blanket 43.

Where desirable, the walls of the refining chamber or zone may be provided with apertures 44 through which a flame from any desired source such as a gas burning flame may be projected to maintain the surface of the material therein at the desired temperature for eliminating the undesirable bubbles, grains or "seed" and thereby making the melt substantially homogeneous. Thus, heating means are provided for both top and bottom sections of the melt in the refining zone. For retaining this zone against excessive heat losses it is also desirable to provide a cover 45 for the refining chamber.

It is also to be noted that cooling ducts 48 or their equivalent are provided in the furnace walls to prevent wall deterioration where the current flow between electrodes touches or tends to touch such walls.

Desirable types of electrodes are shown in Figs. 15 to 20, inclusive.

In Figs. 15 to 17 inclusive, such electrodes have a substantially cylindrical portion 46 provided with an upstanding connection plate 47 having a portion 48 for connection outside the furnace to the electrical bus bars. The connection for each electrode between the submerged portion and the furnace wall is above the molten material. The advantage of this is that if this connecting bar were in the melt, then current would flow from the submerged bar portion through the melt adjacent the furnace wall with resulting excessive heating in zones adjacent the wall and consequent undue wear in the furnace wall.

In Figs. 18 to 20 inclusive, the electrodes are shown as having a modified contact contour as at 49.

In order to maintain the desired heat balance and to prevent overheating of that portion of the electrode in contact with the material to be treated, the connecting plate of the electrodes should have a volume not less than $\frac{1}{3}$ that of the parts 46 and 49.

Obviously, the specific types of electrodes above described as well as the heating means for the furnace bottom or other parts where heat compensation is needed, may be used in any of the various forms of furnaces above described.

While the furnaces have been described with reference to particular embodiments, yet it is to be understood that the invention is not to be restricted thereto but is to be construed broadly and limited only by the scope of the claims.

I claim:

1. A polyphase electric furnace comprising a chamber for the material to be melted and in which the material acts as a resistance, spaced horizontally disposed electrodes therein directed 5 toward a generally common center, two of said electrodes being opposite each other, each of which is connected to a different phase in a three phase electrical system, and two additional electrodes opposite each other and on a line at right 10 angles to a line connecting the first two electrodes, the two latter electrodes being connected to the third phase in the said three phase electrical system.

2. A polyphase electric furnace comprising a 15 chamber for the material to be melted and in which the material acts as a resistance, spaced horizontally disposed electrodes therein directed toward a generally common center, two of said electrodes being opposite each other along a center 20 line of the furnace, each of which is connected with a different phase in a three phase electrical system, and two additional electrodes one on each side of the former and along a center line transverse to the first mentioned center line, 25 both of said electrodes being connected to the third phase in the said three phase electrical system.

3. The furnace of claim 1 in which at least one 30 of said electrodes is subdivided into several electrodes.

4. The furnace of claim 2 in which the distance 35 of the gap between the electrodes on a furnace center line is greater than the gap between either electrode on the transverse center line and either of the center line electrodes.

5. The furnace of claim 2 in which the distance 40 of the gap between the electrodes on the center line is $\sqrt{2}$ times the gap between either electrode on the transverse center line and either of the center line electrodes.

6. A polyphase electric furnace for the material to be melted and in which the material acts as a resistance, comprising a chamber, two electrodes therein opposite each other along the center line 45 of the furnace, each of which is connected with a different phase in a three phase electrical system, and two additional electrodes on each side of the former, both of which are connected to the third phase in the said three phase system, the furnace 50 having a submerged outlet throat through one of the side walls crossed by the center line, the two additional electrodes being located between the transverse center line and the side wall of the furnace through which the submerged outlet 55 passes and all of said electrode entering the melt.

7. The furnace of claim 6 in which the two additional electrodes are on a line parallel with the transverse center line of the furnace, the gap between the electrodes on the line parallel with the 60 transverse center line and the electrode on the center line and adjacent the throat is shorter than the gap between the former electrodes and the electrode opposite that adjacent the throat.

8. A polyphase electric furnace comprising a 65 bottom and side walls forming an operating chamber therebetween, platforms set on the furnace floor and in proximity to the furnace walls, electrodes resting on said platforms, said electrodes being positioned with respect to the side 70 walls so that said side walls are outside of the path of the current passing between all of said electrodes, two electrodes at opposite side walls along the center line of the furnace each connected with a different phase of a three phase

electrical system and two additional electrodes at opposite side walls along a line transverse with the center line both of which are connected to the third phase in said three-phase system, said furnace having a submerged outlet along the center 5 line of the furnace passing beneath the platform and a side wall into an adjoining chamber.

9. The furnace of claim 8 with heat accumulating blocks of a material different from that of which the furnace bottom is made, and means to 10 heat said blocks.

10. The furnace of claim 8, in which the bottom 15 of said chamber consists of refractory material, metal blocks of large volume beneath the same and heating means for said blocks within the same.

11. The furnace of claim 8 provided with a refining chamber and a submerged throat connecting the two chambers, heat accumulating blocks beneath the floor of the throat and the refining 20 chamber and heating means associated with said blocks.

12. An electric furnace comprising side walls and a bottom forming a treating chamber therebetween, platforms placed on the furnace bottom 25 and in proximity to the side walls, electrodes resting on said platforms, said electrodes having a plate-shaped connection rising from the top thereof and extending horizontally out beyond the side wall to a suitable electrical connection, 30 35 the plate-shaped connection being adapted to be covered by a raw material blanket formed on the top of the molten mass within the furnace by the raw material fed thereto, the major portion of the electrode being adapted to be submerged in the molten mass.

13. The furnace of claim 12 in which the connection plate of the electrode represents at least one third of the weight of the electrode part adapted to be below the surface of the molten 40 mass.

14. A polyphase electric furnace comprising a chamber, a submerged throat for the discharge of material treated therein, an electrode on each side of said throat, a third electrode on the other 45 side of said chamber and in line with said throat, the gap between the two electrodes on each side of the throat being so much less than that between said electrodes and the third electrode, that the temperature throughout a horizontal section 50 of the fusing zone will be practically equal.

15. A polyphase electric furnace comprising a chamber, a submerged throat for the discharge of material treated therein, an electrode on each side of said throat, a third electrode on the other side 55 of said chamber and in line with said throat, the gap between the two electrodes on each side of the throat being so much less than that between said electrodes and the third electrode, that the temperature throughout a horizontal section of 60 the fusing zone will be practically equal, the molten charge in the chamber being covered by a thick raw material blanket which is continuously fed to the furnace.

16. An electric furnace comprising furnace 65 walls and a furnace bottom defining a space adapted for containing a conductive bath formed from a superposed layer of raw material to be treated in the furnace, a plurality of electrodes between which current is adapted to flow through 70 the conductive bath, and electrical connections for said electrodes entering the raw material layer for being cooled thereby.

YNGVE R. CORNELIUS.
